(57) **CLAIM**

The ornamental design for a hair dryer, as shown and described.

DESCRIPTION

FIG. 1 is a perspective view of a hair dryer showing our new design;

FIG. 2 is a front elevation view of the design shown in FIG. 1;

FIG. 3 is a rear elevation view of the design shown in FIG. 1;

FIG. 4 is a left side elevation view of the design shown in FIG. 1;

FIG. 5 is a right side elevation view of the design shown in FIG. 1;

FIG. 6 is a top plan view of the design shown in FIG. 1; and, FIG. 7 is a bottom plan view of the design shown in FIG. 1. The dash-dot broken lines shown in the figures represent boundaries of the claim and form no part of the claimed design. All other broken lines depict portions of the hair dryer that form no part of the claimed design.

1 Claim, 7 Drawing Sheets
